STOCKING

Barnett D. Gordon, Brookline, Mass.

Application November 28, 1950, Serial No. 13,157

Term of patent 14 years

(Cl. D47—7)

To all whom it may concern:

Be it known that I, Barnett D. Gordon, a citizen of the United States, residing at Brookline, in the county of Norfolk and State of Massachusetts, have invented a new, original, and ornamental Design for a Stocking, of which the following is a specification, reference being had to the accompanying drawings, forming part thereof.

Figure 1 is a side elevational view of a stocking, showing my new design.

Figure 2 is a fragmentary heel end elevation of the same.

I claim:

The ornamental design for a stocking, as shown.

BARNETT D. GORDON.
